C. HARRIS ET AL

MEANS FOR MOUNTING DOLL HEADS ON BOX LIDS

Filed Dec. 17, 1923

UNITED STATES PATENT OFFICE.

CHARLES HARRIS, OF CHICAGO, ILLINOIS, AND MARTIN A. KATZ, OF CLEVELAND, OHIO.

MEANS FOR MOUNTING DOLL HEADS ON BOX LIDS.

Application filed December 17, 1923. Serial No. 681,065.

To all whom it may concern:

Be it known that we, CHARLES HARRIS and MARTIN A. KATZ, citizens of the United States, and residents, respectively, of Chicago, Illinois, and Cleveland, Ohio, have invented certain new and useful Improvements in Means for Mounting Doll Heads on Box Lids, of which the following is a specification.

10 This invention relates to ornamental receptacles and more particularly to that type of such devices which are in the form of boxes of various shapes and sizes, each being provided with either a hinged or detachable lid or cover, and commonly known as boudoir boxes, and used as receptacles for jewelery, hair-ornaments, handkerchiefs, small powder-boxes and the like.

Many of the boxes of the above named 20 type and to which our invention relates, are elaborately trimmed, inside with satin or other suitable material, and outside with velveteen, velvet, plush or the like, and have their outer walls decorated with silver and gold colored metal lace, while their lids are covered with shirred material of desired color and quality and ornamented with the bust-heads of dolls positioned as if the latter were seated on the upper surface of 25 the box lid and surrounded by the fluffy, and to all appearances, air inflated shirred material which rises and is located directly beneath the hands and arms of the dolls which are extended forwardly and horizontally from the elbows of each.

To obtain and maintain the desired effect of presenting the bust-heads of the dolls as if they were seated on the box lids in the midst of the apparently air inflated shirred material, a considerable amount of filling, such as cotton batting, or the like, must be inserted between the box lid and the shirred material which elevates the latter to such an extent that if the bust of the doll head were 40 mounted directly on the lid in the midst of the shirred material, the latter would cover the arms and hands and thus the desired effect in appearance would be spoiled.

The doll heads used in the manufacture 50 of ornamental boxes of the class to which our invention pertains, are of the type known as "bust-heads," in contra-distinction to that type of doll heads which terminate a slight distance below the juncture of the

neck and shoulders, and have little if any 55 portion of the bust connected thereto.

One of the objects of our invention is, the provision of simple and efficient means for mounting and securing doll heads on the lids of boxes in such a way that they will not become disarranged or dislocated when the 60 lids are opened or removed from the boxes.

Another object is to provide means whereby a doll head may be mounted and secured on the lid of a box in a firm and secure manner, yet, so that it will be properly positioned above an ornamental covering of the lid, when said covering is maintained at a 65 distance above the lid.

Other objects and advantages of the invention will become apparent from the following description and explanation.

In the accompanying drawings, which serve to illustrate an embodiment of the invention,—

Fig. 1 is a face view of an ornamental box with a doll head mounted on the lid thereof according to our invention.

Fig. 2 is a view partly in section and partly in elevation taken on line 2—2 of Fig. 1 looking in the direction indicated by the arrows.

Fig. 3 is a plan sectional view taken on line 3—3 of Fig. 2, and

Fig. 4 is a bottom plan view taken on line 4—4 of Fig. 2.

Corresponding numerals of reference refer to like parts throughout the different views of the drawing.

The reference numeral 5 designates as a 90 whole a box or receptacle which may be of any desired shape but in the present instance is shown as being of an elongated rectangular form. This box may have its outer walls ornamented in any desired way and has its 95 lid 6 covered with upwardly extended shirred material 7, which material may be secured to the edges of the lid 6 by means of glue or otherwise. The shirred material 7 is maintained in its elevated position to 100 present the appearance of being air inflated and in fluffs, by means of filling 8 of cotton batting or other suitable material employed as a packing between the upper surface of the lid 6 and the piece of material 7 which 105 is shirred as before stated and as will be readily understood by reference to Fig. 1 of the drawing. Mounted on the upper sur-

face of the lid 6 at the middle thereof is a supporting block 9 preferably of cork, which is provided with a plurality of vertical openings 10 which are arranged substantially as shown in Fig. 3 and are for the purpose to be presently explained.

The supporting block 9 is by preference substantially cylindrical in cross-section and of a size to correspond with the base of the bust 11 of a bust doll head 12 which is mounted on the upper surface of the supporting block 9. The base or lower portion of the bust 11 has extended vertically thereinto the upper ends of a plurality of slightly ductile wires 13 which are permanently secured in the bust in spaced relation to one another in such a way that they will register with or can be readily extended through the openings 10 in the supporting block employed to support the doll head in an elevated position so that the arms 14 and hands 15 may be extended forwardly just above the shirred material, as will be readily understood by reference to Figs. 1 and 2 of the drawing.

It will be understood that the doll head is extended through the shirred material 7 and the figure may have its shoulders and breast suitably draped and its head covered with a wig of a suitable kind. The lid 6 is provided with a number of openings 16 at proper points to register with the openings 10 in the supporting block so that the wires 13 can be extended through said openings 35 and intertwined as at 17 in Figs. 2 and 4 of the drawing, in which views it will be seen that the lower portions of the wires 13 are extended to a central point between the openings 10 and are then twisted together, which arrangement will firmly secure the bust of the doll head on the upper surface of the supporting block and also said supporting block firmly to the lid of the box.

On the lower surface of the lid 6, a sheet 45 18 of any suitable material may be suitably secured thereto and between said sheet and the lower surface of the box lid, filling or packing 19 of any suitable kind may be employed to hold the sheet 18 at a distance 50 from the lid, by which arrangement it is manifest that the twisted portion of the wires 13 will be concealed.

Secured to the upper surface of the lid 6 by means of cement or glue is the lower 55 portion of a band or strip 20 of strong material such as canvas, which is extended around the supporting block as well as around the lower portion of the bust 11 and secured to said block and bust by means of 60 glue or otherwise. This band is employed to reinforce the connections between the bust and the lid, thereby more firmly securing the doll head in position. By making the sup-

porting block 9 of cork, which is preferably used, and by employing the flexible band 20, it is manifest that a limited degree of resiliency will be afforded to the support for the doll head, thereby reducing the liability of its breakage.

To prevent the wires 13 being pulled through the lid 6 when the same is made of cardboard, a sheet 20^a of fibre or any suitable tough material may be secured to the lower surface of the lid 6 directly under the block 9 through openings in which sheet the wires 75 will be extended before being twisted together at their lower ends. After being twisted together as shown in Figs. 2 and 4, it is manifest that the horizontally disposed portions of the wires 13 will rest on said sheet 20 of tough or strong material.

Having thus fully described our invention, what we claim as new and desire to secure by Letters Patent is:

1. In a device of the class described, the combination with the lid of a box having a plurality of spaced openings in its middle portion, of a block mounted thereon and provided with a plurality of openings adapted to register with those of said lid, a bust doll head mounted on said block, and a plurality of wires fixed at their upper ends in the base of the bust of said head and extended through said openings in the block and lid and intertwined below the latter.

2. In a device of the class described, the combination with the lid of a box having a plurality of spaced openings in its middle portion, of a block mounted thereon and provided with a plurality of openings adapted to register with those of said lid, a bust doll head mounted on said block, a plurality of wires fixed at their upper ends in the base of the bust of said head and extended through said openings in the block and lid and intertwined below the latter, and a re-enforcing band secured around the lower portion of the bust and around said block and at its lower edge to the lid.

3. In a device of the class described, the combination with the lid of a box, of a block mounted thereon at about its middle portion, a bust doll head mounted on said block, a plurality of wires fixed at their upper ends in the base of the bust of said head and extended through said block and lid and twisted together below the lid, re-enforcing means uniting said bust, block and lid and an ornamental covering mounted on and maintained at a distance above said lid, said covering surrounding the bust of the head just above the upper end of said block.

CHARLES HARRIS.
MARTIN A. KATZ.
